O. POOLE, OF DETROIT, MICHIGAN.

Letters Patent No. 74,419, dated February 11, 1868.

IMPROVEMENT IN CULINARY BOILERS.

The Schedule referred to in these Letters Patent and making part of the same.

TO ALL WHOM IT MAY CONCERN:

Be it known that I, O. POOLE, of Detroit, in the county of Wayne, and State of Michigan, have invented a new and improved Culinary Steamer; and I do hereby declare that the following is a full, clear, and exact description thereof, which will enable others skilled in the art to make and use the same, reference being had to the accompanying drawings, forming part of this specification.

This invention consists in an arrangement whereby various articles of diet may be cooked by steam at the same time in separate compartments, and in one and the same boiler, as I will proceed to describe.

The drawing represents a vertical section of the whole arrangement, showing the stove-boiler, the steamer, and the steam-baskets.

The boiler is made in a rectangular form, and may be of any desired size. A is the boiler, constructed of tin, with copper bottom, or of any suitable materials. B is a steamer, the sides and bottom of which are perforated, and in this example of my invention it occupies about two-thirds of the upper portion of the boiler, as seen in the drawing. This steamer is supported in its place by a bead on the inside of the boiler, as seen at *a a*. This bead extends around the whole inside of the boiler. C is an upright partition, which divides the boiler into two compartments. D and E are baskets made of perforated metal or wire cloth, which set into the steamer B side by side. These baskets have flanges around their tops, from which they are suspended on the top of the steamer. F is another basket, constructed in the same manner, and which is suspended by its flange on the bead *a* in the boiler. Each of these baskets has a cover and loops on its rim for convenient handling, which loops are marked *e*. *d* is the boiler-cover. Should it be desired to use the baskets D and E separate from each other, a partition, G, (seen in detailed view,) may be slipped down into the boiler after removing the steamer B. The ribs which support this partition are seen in the boiler at *f*. The bottom of the steamer B is concave longitudinally, so that any grease which may find its way to the bottom will be conducted to the middle, and be discharged from thence into the trough H. This trough or spout has a faucet at the end outside the boiler, as seen at J, from which the liquid is discharged into any vessel placed to receive it.

Water is of course placed in the boiler, and when the boiler is not used for cooking it can be made available for other purposes, like ordinary stove-boilers. It will thus be seen that various kinds of meats and vegetables, or other articles of diet, may be cooked at the same time, in separate compartments, and that the steamer and baskets are readily removed for cleaning or for other purposes.

What I claim as new, and desire to secure by Letters Patent, is—

In combination with the boiler A, perforated baskets D, E, and F, and removable partitions C and G, the spout H, constructed and arranged substantially as herein described and for the purpose set forth.

O. POOLE.
